UNITED STATES PATENT OFFICE.

GEORGE M. EAMES, OF BRIDGEPORT, AND GEORGE W. JACQUES, OF STRATFORD, CONNECTICUT, ASSIGNEES TO THE SINGER MANUFACTURING COMPANY, A CORPORATION OF NEW JERSEY.

MACHINE FOR SETTING FASTENERS IN SHEET MATERIAL.

Application filed October 31, 1917. Serial No. 199,498.

To all whom it may concern:

Be it known that we, GEORGE M. EAMES, and GEORGE W. JACQUES, citizens of the United States, residing at Bridgeport and 5 Stratford, respectively, in the county of Fairfield and State of Connecticut, have invented certain new and useful Improvements in Machines for Setting Fasteners in Sheet Material, of which the following is a 10 specification, reference being had therein to the accompanying drawings.

This invention relates to machines for setting fasteners in sheet material such for example as the uppers of boots and shoes, 15 and is herein shown as embodied in a machine of the duplex type for setting eyelets in each of two superposed pieces of such material, but it is to be understood that many of its features may be advantageously 20 employed in eyeleting machines of other types as well as in machines designed to set fasteners of other kinds such as lacing hooks, or studs.

Machines of this type as known commercially at the present time are subject to many 25 defects in operation among which may be mentioned great complexity of parts resulting in high cost of manufacture and upkeep, uncertainty in action especially when attempts are made to run them at high speed, 30 due to the use of spring control of many of the essential operating parts, as well as failure to supply proper means for supporting, holding and guiding the work while being 35 operated upon.

It is the object of this invention to overcome the above defects and difficulties as well as other and minor disadvantages inherent in the old types of machine but not 40 pointed out in detail above.

More specifically, it is an object of this invention to so construct a machine of this character as to avoid undue complication of parts while at the same time retaining all 45 the advantages of adjustment and adaptability to various types of work possessed by the old machines.

It is a further object of the invention to obtain the feeding action or the punching and setting operation or both by mechanism which gives a positive control of such

operations at all times both on the active and return strokes of the parts, thereby avoiding the use of springs and permitting of driving the machine at all speeds with 55 equal certainty of operation.

It is another object of the invention to provide an improved form of hammer, or punch and set operating device, providing for ample relative adjustment of the stroke 60 of the punch and set in operating upon the work.

Another object of the invention is to provide improved means for supporting and guiding the work while being operated 65 upon, said guiding means being adapted for ready adjustment and also serving as a hold-down for the work during withdrawal of the set from the clinched eyelet.

An important feature of the invention 70 and one which is believed to be broadly new in this class of machines comprises a work hold-down or presser-foot device for holding the work in position upon the work support, this device being always under tension 75 of a light spring to hold the same against the work support, but being automatically subjected to heavy tension at the moment of operating upon the work. Means, herein disclosed as embodied in the presser-foot, 80 but which might be incorporated in a separate element, if desired, is also provided for constantly feeding the work toward the edge-gage to insure proper alignment of the fasteners. 85

Other features of the invention, in addition to those above referred to and including important details of construction and improved combinations of parts, the advantages of which will be clear to those 90 skilled in the art will be hereinafter more particularly described and claimed.

These and other features of the invention will be best understood and appreciated from the following description of a preferred embodiment thereof selected for purposes of illustration and shown in the accompanying drawings in which,— 95

Fig. 1 is a front elevation of the machine, tipped backward to more clearly show the 100 construction. Fig. 2 is an elevation of the left hand side of the machine of Fig. 1.

Fig. 3 is a plan view of the machine as shown in Fig. 1 certain parts relating to the eyelet feeding means being broken away for the sake of clearness of illustration. Fig. 4 is a vertical section taken on the line A—A of Fig. 3. Fig. 5 is a detail end view of parts shown in Figs. 2 and 9. Fig. 6^a is a perspective showing details of a modified and preferred form of lifting means for the punch and set devices. Figs. 6, 6^b, 7 and 8 are detail views illustrating the construction and operation of the punch and set devices. Fig. 9 is a detail view of the mechanism for controlling the position of the delivery ends of the eyelet races. Figs. 10 and 10^a show details of the anvil, work support, and edge-guides. Fig. 11 is a detail view of the cam for operating the punch and set devices. Fig. 12 is a front elevation of the right hand side of the machine showing the clutch mechanism and cooperating parts. Fig. 13 is a sectional end elevation taken on the line B, B (Fig. 12) and showing the clutch elements in neutral position. Fig. 14 is a detail view of the clutch elements disassembled. Fig. 15 is a sectional detail of the locking device for the clutch elements. Fig. 16 is a front elevation showing the fastener feed mechanism of the machine. Fig. 17 is a plan view of the structure shown in Fig. 16. Fig. 18 is a sectional view through the hopper device of the feed mechanism and Fig. 19 is a detail view of the gate-member and its supporting parts, removed from the hopper.

Frame and drive mechanism.

The base of the machine is indicated at 1 this base being of any suitable form adapted to be mounted upon a bench or other support. Extending upwardly from the base member are a series of supporting arms or brackets 2, 3, and 4 which brackets may be integral with the base member as herein shown or may, if desired, be formed as separate members. Of these brackets two adjacent brackets 3 and 4 are extended upwardly and forwardly as clearly indicated in Fig. 2 and provide at their upper ends aligned bearings 5 and 6. At a point near the lower ends of the supporting brackets 3 and 4 a second pair of aligned bearings 7 and 8 is provided. The purpose of the above set of bearings will be hereinafter described.

At the upper end of bracket 2 is provided a bearing 9 and in alignment therewith in bracket 3 is provided a second bearing 10, these bearings forming a support for the main drive shaft to be hereinafter described. Formed upon the upper part preferably of the central bracket 3 is an inclined supporting surface 11 and projecting outwardly from the rearward part of the same bracket 3 is a secondary bracket 12 also provided at

its upper portion with an inclined supporting surface 13. The base member with the brackets projecting upwardly therefrom having the bearings and supporting surfaces described constitutes the frame of the machine and it will be noted that this frame as disclosed is formed as a single integral casting, thus producing an extremely simple and cheap construction requiring very little machine work to adapt it for supporting the various parts of the machine. While as stated this structure is shown as an integral casting it is to be understood that it is fully within the scope of this invention to form the frame of several independent elements suitably connected together. The main purpose of this feature of the invention, however, is to provide a simple and strong supporting structure for the operative parts.

In machines of the present type as heretofore constructed it has been found desirable to mount the work-rest and the operating tools in an inclined position with respect to the horizontal plane in order to present the surfaces of the work in a plane normal to the line of vision of the operator. In previous machines it has usually been found necessary to employ specially formed interposed supporting devices between the frame and the various operating parts in order to properly position the latter in an inclined position as above described, but by reason of the arrangement in this machine of the supporting brackets having their upper ends forwardly inclined as above described and the provision of forwardly inclined supporting surfaces such as 11 and 13 it is possible to directly support all of the operative parts of this machine in the desired inclined position upon the frame structure thus again tending to simplify the machine and to decrease the cost of production of the same. This is believed to be a valuable feature of the invention and has been broadly claimed herein.

The main drive shaft is indicated at 14 and is shown as provided upon its right hand end with the usual hand-wheel 15 fixed thereto. Located upon the drive shaft between the hand-wheel and the bearing 9 is a drive mechanism including a clutch indicated generally by reference letter a. Mounted between bearing 9 and bearing 10 is a feed-cam 16, a tool operating cam 17, and a pulley 18. Fixed upon the left hand end of said drive shaft and extending beyond the bearing 10 is an eccentric pin 19 (see Fig. 9) the purpose of which will be later described.

The clutch mechanism above noted may be of any suitable type but is here shown as of the form known as the Horton clutch, an example of which may be seen in patent to Horton, 260,394, July 4, 1882, to which reference may be had for a disclosure of this general type of mechanism. It is believed

- sufficient herein to describe this clutch generally as comprising a collar 20 fixed upon the shaft said collar being provided with a stop-lug or shoulder 21, a bearing boss 21', 5 a double cam-member 22 and an out-standing pin 23. Cooperating with said collar is a clutch-ring 24 rotatably mounted upon the boss 21' and provided with an out-standing pin 25. This clutch-ring 24 is provided 10 with a flange 26 providing in connection with boss 21' a recess for a spring 27 said spring bearing at its opposite ends upon the respective pins 23 and 25. Pins 23 and 25 may be at different radial distances from 15 the center of the supporting shaft and by this arrangement the spring can be readily inserted within the receiving cavity of the clutch-ring 24 with one end bearing upon the pin 25 and the clutch-ring 24 may therefore 20 after be mounted upon the collar 20 with the pin 23 of the latter freely passing the pin 25 to engage the other end of the spring.
- The clutch-ring 24 is provided with a pair 25 of slots 28 forming receptacles for the clutching devices 29 shown as blocks freely slidable thereon. These blocks each comprise a substantially rectangular base portion having parallel bearing surfaces 29' adapted to slide within the guiding walls 28' 30 of slots 28, a curved surface acting as the clutch element and a semi-cylindrical bearing or seat at its opposite face for a cylindrical roller 29'', the latter engaging cam surface 22'. 30 indicates a drive pulley having a hollow boss 31, the latter providing a clutching surface 32 for engagement with the curved surfaces of clutch-blocks 29 when the latter are thrown into clutching relation, the pulley being loosely mounted on the drive 35 shaft between the band-wheel 15 and collar 20, and having its boss so positioned as to enclose the portion of clutch ring 24 containing slots 28. 32' indicates an opening formed in the collar 20, said opening being 40 shouldered at 33 and being screw-threaded at 34. Engaging said screw-threads 34 is the threaded portion of a flanged bushing 35. Slidably mounted within the said bushing and extending through the opening 32' 45 is a coupling pin 36 said pin being provided with a flange 37 and with a portion 38 projecting beyond said flange. Seated within the cavity formed between the collar 35 and the flange 37 and within the opening 32' is a 50 spring 38', said spring acting normally to press the pin 36 in a direction away from the bushing thereby to project the end 38 of the pin beyond the face of the collar 20. Mounted upon said bushing 35 or integral 55 therewith is a hollow, cylindrical extension 39 said extension being provided with an inclined slot 40. Fixed in the outer end of the pin 36 is a handle member 41 projecting outwardly through the slot 40. It is evident 60 from the inspection of the construction 65 shown that rotary movement of the handle member 41 about the axis of the pin 36 will cause an outward movement of the pin 36 against the tension of the spring 38 by reason of the engagement of the pin 41 with the inclined walls of the slot 40. The slot is provided at its end with an enlargement 42 serving as a seat for holding the handle in fixed position when the latter is brought 70 into engagement with said enlargement. Cooperating with the extending end 38 of the pin 36 is an opening 43 in the clutch-ring 24. The clutch-ring 24 is further provided with a stop shoulder or lug 44, said lug when the parts are assembled, facing in a direction 75 opposite to that of the lug 21.
- Upon the base of the machine directly below the location of the clutch member is an outstanding lug 45 said lug having an opening 46 extending therethrough. Fixedly 80 mounted upon said lug or integral therewith is a block 47 forming a base or support and upon this base or support is located a relatively thick annular washer of resilient material 48, this washer serving as a buffer 85 member. It is clearly evident, however, that other equivalent means may be substituted therefore such for example as a coiled spring. 49 represents a cup or cover adapted to slidably engage the outer surface of the 90 block 47, forming a cap for the same and thereby enclosing the washer. Mounted to slide within the opening 46 in the lug 45 and extending up through the washer 48 and through an opening in the top of the cover 95 49 is a rod 50 said rod being guided at its upper end in an opening in a second bracket 51 fixed to the frame of the machine.
- Suitably mounted upon the rod 50 is a yoke member 52, this member being shown as 100 adjustably fixed upon the rod by a set-screw 53. Located between the bracket 51 and the yoke 52 is a coiled spring 54 which tends to constantly keep the yoke 52 in engagement with the top of the cover member 49. Pivotally 105 mounted upon the ends of the yoke member at the points 55 and 56 respectively are a pair of stop-arms 57 and 58, said stop-arms being normally moved toward each other at their upper ends by a spring 59 at- 110 tached at its opposite ends to the respective arms. Arms 57 and 58 are provided near their central portions with oppositely inclined cam-members 60 and 61 respectively. Pivotally supported upon an upper exten- 115 sion 62 of the bracket 51 is a rocker-member 63 provided with an outwardly extending arm 64 and with a pair of oppositely extending cam-engaging arms 65, 66, said arms being adapted to engage the cam surfaces 60 and 61 respectively. Connected to the end 120 of the arm 64 is any suitable device adapted for control by the operator, herein shown as a rod 67 adapted for connection to a suitable treadle device. The stop-arms 58 and 57 are 125 130

provided at their free extremities with stop surfaces 69 and 68 adapted for engagement with the stop-lugs 44 and 21 of the clutch-ring 24 and the collar 20. The operation of this clutch mechanism will now be obvious.

In the drawings (Figs. 12 and 13) the machine is shown as at rest, the stop arms being in engagement with the stop lugs of the clutch device, clutch-blocks 29 being shown in neutral position. At this time the spring 27 is under compression tending to turn the clutch member 24 with respect to the collar 20 but is restrained from such movement by the engagement of the stop devices. Upon movement of the lever 64 the arms 65 and 66 engage the respective cam surfaces 60 and 61 of the stop arms thereby separating the free extremities of the stop arms and thus disengaging them from the stop lugs. At the instant of release of the lug 44 from its stop arm the spring 27 expands thereby causing a partial rotation of the clutch-ring 24. This movement causes the clutch blocks 29 to ride up upon the cam surfaces of the cam 22 and thereby clutches the continuously rotating pulley 30 to the drive-shaft permitting a positive drive of the same. Upon release of the treadle or other means for controlling the arm 64 the spring 59 which is under tension draws the free ends of the stop arms 57 and 58 toward one another and into the path of the stop lugs 21 and 44. Upon engagement of the lug 44 with its stop arm the ring 24 is stopped and the cam 22 rides out from beneath the clutch-blocks 29 thereby releasing the driving shaft so that the momentum of the machine puts the spring 27 under tension. At the instant of release of the drive shaft the stop-arm 57 goes beneath the lug 21 and thereby prevents reverse rotation of the shaft. It will be noted that by reason of the interposition of the buffer member 48 between the stop-arms and the frame of the machine the shock due to sudden stoppage of the parts is to a large extent absorbed, thereby avoiding undesirable strain in the machine parts.

During the normal operation of the machine the pin 36 is in retracted position the handle 41 being located in the enlargement 42 of the slot 40 thus providing for independent movement of the collar 20 and the clutch-ring 24. It is at times desirable to turn the drive shaft by hand while the driving pulley is still running, but it is evident that in the series of operations above described this is impossible for as soon as the stopping devices are thrown out of action the drive-pulley is clutched to the shaft for driving the same and upon stopping the machine the drive-shaft is positively locked against manual operation. The purpose of the pin 36 is to permit of such manual con-

trol of the drive-shaft with the machine stopped.

Upon release of the pin 36 by manipulation of the handle 41 the spring 38 projects said pin to such a position as to cause its end 38 to engage the opening 43 in the clutch-ring 24 thus positively locking the ring and collar together. It will now be evident that if the machine be stopped and the pin 36 thus released to couple the parts together, the stop arms may be retracted from the stop lugs without any operation of the clutch elements, the clutch-ring 24 being restrained from turning movement under action of the spring 27 by reason of the locking engagement of the pin 36. The drive shaft is now free from the stopping devices and also free from the drive pulley and may thus be turned freely by hand for adjusting the various mechanical parts or for any other desired purpose, it being evident that by this operation the drive shaft may be turned by hand without the necessity of turning the countershaft and intermediate driving connections. Whereas in clutches of this type as heretofore known wherein a stop-arm is employed, a large unbalanced force has been developed which must all be absorbed by the machine frame, in this device the arrangement of the stop and reverse arm upon the same support and upon opposite sides of the shaft, together with the manner of mounting the support serves to balance the thrust developed in stopping, thus relieving the adjacent frame parts of undesirable strain to a very large extent. No claim are made herein to the specific clutch mechanism above described, which mechanism forms the subject matter of copending application Serial #199,486, filed October 31, 1917, by George M. Eames.

Tool operating mechanism.

Located in the aligned bearings 5, 6 and 7, 8 are a pair of shafts 70 and 71 having fixed thereto between said bearings the respective arms 72 and 73, said arms being provided near their outer extremities with suitable hammer devices for operating the fastener setting tools. Rigidly attached to the shaft 70 is a crank-arm 74 and attached to the adjacent end of the shaft 71 is a similar crank-arm 74'. Carried upon the outer extremity of the respective crank-arms are cam engaging rolls 75 and 76, (see Fig. 11) said rolls being adapted to engage cam-grooves 77 and 78 formed upon the opposite lateral faces of the tool operating cam member 17, the latter being fixed to the drive shaft. The cam-grooves 77 and 78 are adapted to swing the crank-arms 74 and 74' and thereby the hammer carrying arms 72 and 73 positively in both directions of movement thereby avoiding the necessity for the use of resilient retracting means for

said parts as is common in the prior art construction.

Reference may be had to Figs. 6, 6^b, 7 and 8 of the drawings for the detailed construction of the hammer device. As the hammer members for both the upper and lower fastener setting devices are of similar construction it will be sufficient to refer to the construction of the upper of these devices. The hammer arm 72 is bifurcated at its outer extremity to form two opposing arms 80 and 81. Fixed upon the upper surfaces of these arms by suitable fastening means as screw 82, see Fig. 3, is an angular plate 84 said plate forming a cover for the space between said arms and also serving as a closure for the space between the extremities of said arms.

Located within the chamber thus formed between the arms 80 and 81 and the plate 84 is a vertically slideable plate 85 said plate being vertically adjustable by means of a screw 86, said screw being provided with a suitable locking means 87 for holding the same in said position. Also located within said space and vertically adjustable is a U-shaped frame 88 having the closed side 89 thereof in engagement with the plate 85, said frame 88 being suitably frictioned against the walls of said space by set-screws 90 and 91, and a plate 91' is interposed between screw 91 and the ends of frame 88. The arms of said U-shaped frame are provided with inclined grooves 92. Slidable within a suitable slot 93 in the cover-plate 84 is a block 94 said block being supported in said slot by a plate 95 overlapping the edges of said slot and secured to said block by a screw 96. The block 94 is provided with oppositely projecting tongues 97 adapted to take into the inclined grooves 92 of the U-shaped frame. An adjusting screw 98 is threaded through one arm 81 of the hammer-lever and has a positive connection of any suitable character, permitting relative vertical movement between said parts, with the slide-block 94 whereby movement of the screw in or out produces a sliding movement of similar character in the block 94. Suitable locking means 99 may be provided for the screw 98. From the above construction it will be clearly evident that the plate 85 may be vertically positioned by the adjusting screw 86 and that the vertical position of the U-shaped frame 88 may also be adjusted by turning the screw 98 thereby causing a sliding of the block 94 which through the tongues 97 acting in the inclined groove 92 of said frame produces a vertical adjustment of the latter.

Punch and set mechanism.

The machine disclosed is provided with a telescopic punch and set mechanism, the punch being located within the tubular set,

the punch and set being laterally movable for setting the work and being respectively operated at different times during such movement. This machine is of the duplex character employing oppositely disposed punch and set devices. As the two punch and set mechanisms are substantially identical it is believed to be sufficient if one of these is described, and reference may be had to Figs. 2, 3, 4, 6, 7 and 8 for a full disclosure of these parts. As previously stated the central bracket of the frame is provided with an inclined supporting surface 13. Fixedly mounted upon this supporting surface is a bracket 100 said bracket being provided with a vertically extending portion 101 having at its upper and lower extremities suitable bearings 102, 103. Mounted within these bearings are adjustable pintle pins 104, said pins being adapted to be fixed in adjusted position by means of set-screws 105. Supported between said pintle pins and for pivotal movement therein is a lever member 106 said member being provided with suitable bearings 107. The lever member 106 is herein shown as of substantial vertical depth and as being bifurcated at its free end to provide two opposed arms 108, 109 provided with bearings 110, 111 at their respective outer ends. Mounted to slide vertically within said bearings are the fastener inserting tools and as this machine is of duplex form and the opposed sets of tools are identical it is believed sufficient if one of these sets of tools is herein described.

Referring now particularly to Figs. 6, 7 and 8 it will be noted that within the bearing 110 is slidably mounted a sleeve 112 said sleeve having formed at one extremity an enlargement or head 113, this head serving to receive the blow of the operating hammer. The opposite extremity of said sleeve 112 is counterbored to provide an enlarged chamber 114 thus forming at the inner extremity of said chamber a shoulder 115. The outer extremity of said sleeve is screw-threaded internally at 116 and is adapted for screw-engagement with the fastener setting tool 117 the latter being shown as provided with an integral sleeve 118 projecting within the chamber 114 and providing by its upper extremity a second shoulder 119 opposed to said first named shoulder. Mounted to slide within the sleeve 112 is a hollow punch supporting shank 120 said shank being provided at its lower end with an outwardly projecting flange 121. In the chamber 114 and between said shoulder 115 and the flange 121 is located a coil spring 122 said spring having its bearings upon the shoulder 115 and the collar 121 thereby tending constantly to project the shank 120 in a direction toward the setting tool. Located within the hollow setting tool is a hollow punch 123 said punch being provided at its rearward

extremity with a flange 124 and with a central teat 125 said teat being located within the lower extremity of the shank 120 and serving to center the punch within the same.

5 The shoulder formed by the extremity 119 of the set 117 serves as a stop against which the flange 124 bears to limit the movement of the punch in an outward direction, the spring 122 tending always to keep the collar 121 upon the shank 120 in contact with the flange 124.

Any suitable means may be provided for normally moving the punch and set devices to inoperative position such means being 15 herein shown as a lever 126 pivotally mounted upon a lug 127 extending from the arm 108, said lever being bifurcated at its free end to provide arms 128 adapted to engage beneath the enlarged head 113 of the hollow 20 sleeve 112, said lever 126 being normally tensioned by a spring 129 bearing against the same in a direction tending to move the punch and set to retracted position.

A modified type of mechanism for retracting the punch and set devices is illustrated 25 in Fig. 6^a of the drawings, this being a very simple and satisfactory arrangement and the preferred form, and that which is claimed herein. Upon the hammer-lever 72 is a boss 30 72^a having a machined surface 72^b forming a bearing for a forked arm 72^d, the latter being pivotally mounted to swing upon said bearing surface by a pin 72^c. At its forked extremity the arm 72^d is adapted to take under the enlarged head 113 of the hollow sleeve 112. The arms of lever 72^a are shown at 72^b as humped up slightly near their outer ends to provide a better bearing for engagement with the head of sleeve 112. It will 35 readily be seen that with the above construction upward movement of lever 72 in retracting the hammer, serves by reason of the engagement of lever 72^d with head 113, to positively lift the sleeve 112 and that the 40 pivotal mounting of lever 72^d permits the same to follow sleeve 112 in its lateral feed movement, thereby maintaining a constant engagement between the parts. It will be obvious that lever 72^d may be of some resilient material as for example spring steel to avoid unnecessary shocks in operation or if desired to retain the head 113 always in contact with the hammer member.

Fixedly mounted upon the lever-arm 106 45 near its forward end is an anvil supporting member 130 said anvil member being provided with a combined punch-anvil and setting tool 131, such tool being removably secured in said support by means of a pin 132 50 the punch-anvil and setting tool being of old and well-known character such as is commonly employed in machines of this type. In the present machine however, the pin 132 engages the member 131 loosely, thereby providing for a slight freedom of movement of

the latter with respect to the support 130, a feature which is desirable in a machine of this type, enabling the part 131 to automatically center itself with respect to the oppositely acting punches and sets.

70

Feeding mechanism.

In this machine the material operated upon is fed by a lateral movement of the punch and the means for securing this movement will now be described. As herein shown the lever-arm 106 is provided near its forward end with a lug 132, see Fig. 3, and pivotally secured to said lug is a link 134. Fixedly mounted upon the cam-shaft as previously noted, is a feed-cam 16, see Figs. 1 and 3, provided with a suitable cam-groove 135.

75

Projecting rearwardly from the upper portion of the bearing bracket 2 is an arm 136 provided at its extremity with a bearing 137 for a vertical shaft 138, (see Fig. 1) said shaft being mounted at its lower end in a suitable bearing 139 carried by the base of the machine and in alignment with said first mentioned bearing. Fixed to the upper end of the shaft is a lever-arm 140 and mounted loosely upon the shaft 138 by means of a pair of spaced bearing lugs 139, is a bell crank lever 141 shown in Fig. 1 as just above one of the bearings 139, said lever being provided with an arm 142 having its extremity connected by means of a link 143 to the link 134 whereby movement of the bell crank-lever 141 about its pivot will produce a 100 swinging movement of the link 134. The other arm 143 of said bell crank-lever is provided with suitable mechanism under control of the operator, herein shown as a chain 144 suitably guided and adapted to be connected to a foot-treadle whereby movement of the treadle serves to turn said lever, it being obvious, however, that other and equivalent means may be substituted for the above controlling devices.

90

Surrounding the shaft 138 is a coiled spring 145 (see Fig. 1) having one end thereof secured to the bell crank lever 141 and having its other end bearing upon the frame of the machine, said spring being so tensioned as to normally tend to move the bell crank-lever in a clockwise direction as seen in Fig. 3 of the drawings. The lever 140 is provided with a T-shaped slot 146 said slot as seen in plan being of arcuate 115 form, the curvature of said slot being concentric with the pivotal connection of link 134 to lug 132 when the parts are in initial position with the punch located for the punching operation. Slidable in said T-shaped slot is a bolt-head, the bolt projecting upwardly therefrom as seen at 147, said bolt extending freely through an opening formed in the end of link 134 and being provided with a nut 148 whereby the link 130

105

110

115

120

125

130

may be properly secured in position upon said bolt. Also secured within said slot and upon opposite sides of the link connecting bolt 147 are stop bolts 149 and 150 said bolts being provided with suitable nuts for locking the same within the slot. It is evident that by loosening the nuts said bolts 149 and 150 may be adjusted to different positions in the slot and may thereby serve to limit the movement of the link connecting bolt 147 in said slot and to different paths of movement therein. By reason of the spring-tension of the bell crank-lever 141 and the connection thereto of the link 134 by the link 143, the link 134 tends to move in a counter-clockwise direction as seen in Fig. 3 or toward the fulcrum of the lever 140 and it will be noted that upon movement of the lever 141 by the operator the position of the bolt 147 and the link 134 may be varied within the limitation imposed by the positions of the stops 149 and 150. Fixed to the lever 140 is a lug 152 said lug being provided as shown in Fig. 1 with a cam engaging roll or stud 153 said stud being located within and adapted to be actuated by the cam groove 135.

Upon operation of the drive shaft the cam 16 through the lever 140 and the link 134 will cause a rocking movement of the lever 106 and thereby will cause a lateral swinging movement of the punch and fastener setting device. As the cam actuates the roll 153 positively in both directions, it will be seen that the arc of travel of the lever 140 is constant but by reason of the adjustable connection of the link 134 to said lever whereby the effective length of the lever as a means for moving the link may be varied, the arc of travel of the lever 106 and therewith the punch device may be varied. By reason of the fact that the slot in lever 140 is formed as a circular arc about the pivotal connection of link 134 to lug 132, when the parts are in normal position adjustment of the link 134 will not vary the initial position of the lever 106 or of the punch carried thereby but will merely adjust the length of travel of these parts.

The operation of the punching and setting devices may now be briefly described. With the parts shown as in Figs. 1, 3 and 6 the lever 106 is in initial feed position, the punch and set being fully retracted. Upon operation of the drive shaft the cam groove 135 being provided with a dwell at this point retains the said lever 106 in initial position. The hammer operating cams 77 and 78, however, are provided with active elements at this point and produce a striking movement of the hammer. This movement is only sufficient to partially project the setting device by contact of the U-shaped frame 88 with the head 113 but at the same time causes contact of the plate 85 with

the upper extremity of the shank 120 of the punch, the movement of the hammer being sufficient to cause the punch to engage the work and form an opening therein, the set, however, not being projected far enough to come into contact with the work, it being understood that in its outward movement the punch has been supplied by suitable means with a fastener, such for example as an eyelet.

Upon a further turning movement of the drive shaft the feed-cam 16 which is here provided with an advancing portion causes a lateral swinging movement of the lever 106 and therewith of the punch and set devices, this lateral swinging movement serving to move the hammer engaging portion of the shank of the punch out from under the plate 85, the punch at this time resting upon the anvil 131 which it will be understood partakes of the lateral movement of the punch and set so as always to be in registering relation thereto. The cams 77 and 78 now present a further operative portion which causes increased movement of the hammer members, and as at this time, as before stated, the punch shank has been removed from below the slide 85, no further action of the punch will take place, the upper portion of the shank thereof as indicated in Fig. 8 being free to extend between the arms of the U-shaped frame 88, under increased pressure of the punch upon the anvil. The arms of said frame, however, in the further downward movement of the hammer bear heavily upon the enlarged upper extremity 113 of the set-carrying sleeve 112 and thereby depress the set into engaging relation with the fastener to clinch the same in the opening in the material. The cams 77 and 78 now present a retracting portion which upon further rotation of the shaft causes the hammer devices to be returned to inoperative position while at substantially the same time the feed-cam 16 presents a retracting surface adapted to cause return movement of the lever 106 and thereby of the punch and set mechanisms to initial feed position. This cycle of operations is repeated upon each rotation of the drive shaft thus producing successive punching and setting actions and feed movements of the material intermediate of such actions it being clearly evident that by reason of the engagement of the punch with the material during the lateral swing of the punch, the material must be fed along therewith.

Fastener feeding mechanism.

The machine is provided with automatic means for supplying fasteners to the punching and setting tools and such fastener supplying means is hereinafter set forth.

Mounted upon the inclined supporting

surface 11 of the central bracket is an arm 154 said arm being provided with a foot 360 pivotally mounted at its rear end by means of the bolt 351 and being provided at 5 its forward end with a slot 350. Passing through said slot into the supporting surface is a bolt 352 by means of which the arm 154 may be adjustably fixed in position laterally of the supporting surface. 10 Such adjustment is desirable at times for adjusting the delivery ends of the raceways which are supported at their upper ends by devices carried by said arm 154, the purpose of such adjustment being hereinafter described. The arm 154 is provided at its outer extremity with an inclined bearing boss 155. Loosely supported within said bearing is a sleeve 156, said sleeve having integral therewith or fixed thereto a plate 157 resting upon the upper extremity of 20 said bearing 155. The plate 157 forms the base of the receptacle for fasteners, said base being provided with a series of brackets 158 adapted to removably support 25 a drum or hopper 160, suitable means such as bolts and wing nuts 159 being provided for holding the parts in fixed relation.

The hopper 160 may be provided in its upper wall with a suitable opening for filling the receptacle with fasteners. As illustrated herein automatic means may be provided for feeding fasteners to said hopper through the opening formed therein and such means may consist of a suitable reservoir 161 supported upon a bracket 162 from the frame of the machine and having a feed-spout 163 extending downwardly through the opening into said hopper, said reservoir being adjustably supported upon its bracket 40 whereby to vary the distance of the extremity of the feed-spout from the bottom of the hopper thereby serving to provide means for adjusting the feed of fasteners to the hopper. Such hopper supplying means is well known and no claims are made herein to this structure.

Mounted for rotation within the sleeve 156 is a shaft 164, said shaft having fixed at its lower end a gear 165 and having mounted 50 upon its upper end a dished-plate 166, said plate being attached to the shaft by any suitable means such as a screw 167, the convex portion of said plate being uppermost. Within the rim of said plate are a series of 55 radial openings 168 adapted for the reception of individual brush-tufts 169, the arrangement being such that the tufts extend outward in a direction substantially parallel to radial elements of said convex surface of 60 the plate, that is to say, in a direction somewhat inclined to the shaft 164. Such tufts may be provided with ferrules 170 of any suitable material adapted to hold the bristles of said brush in proper relation, said ferrules fitting within the openings formed in

said plate and being independently secured therein by set-screws 171 or by any other suitable means.

In machines of this type as heretofore known, no means has been provided for the renewal of one or more of the brush tufts if, as frequently happens, such tufts become loose or worn before the remainder of the brush, thus necessitating removal of the entire agitating device and substitution of a new one, whereas by applicant's construction one or more individual brush tufts may be renewed at slight cost and small expenditure of time and labor, the desirability of which will be understood by those skilled in the art. 70 75 80

While the above method of securing the brush to the plate is a preferred form it is not to be understood that this invention is limited to the specific means shown as it is clearly evident that any other suitable equivalent means may be substituted therefor within the scope of the claims herein presented. 85

Mounted upon the upper end of shaft 164 and above plate 166 is a convex supporting or baffle plate 400. This plate may be secured to the shaft in any suitable manner as by means of the same screw 167 as is employed for holding plate 166 thereto. This supporting plate is of a diameter slightly less than that of the agitator extending as herein shown to cover all but substantially the outer half of the brush tufts, thus leaving only a narrow circumferential channel between its edge and the wall of the hopper for the passage of fasteners downward into the path of the brush. 90 95 100

The purpose or function of this plate is to support the mass of fasteners in the hopper, thus relieving the brush tufts of this 105 duty to a large extent and resulting in only a comparatively small number of fasteners being swept around by the brush and presented to the discharge opening. In many machines of the prior art difficulty has been 110 experienced, especially when the hopper was well filled or when attempts were made at automatically replenishing the hopper from a supply reservoir in securing a uniform and steady flow of fasteners from the discharge opening, but by provision of the baffle plate herein disclosed, the above difficulty has been overcome. Projecting from the supporting arm 154 are a pair of lugs 172, said lugs being provided with aligned bearings within which is supported a shaft 173 said shaft being provided at its outer extremity with a gear 174 meshing with the gear 165 and being provided at its opposite extremity with a pulley 176, (see Fig. 1). 115 120 125 Pivoted upon a convenient portion of the frame is a lever 177, (see Fig. 2) said lever being provided at its free extremity with a stub-shaft 178 having freely mounted upon the same a pair of guide-pulleys 179, (Fig. 130

3). The lever 177 is also provided near its center portion with an adjustable set-screw 178 adapted to contact with the frame of the machine and thereby form an adjustable 5 stop for said lever. Passing about the pulley 176 and the pulley 18 upon the drive-shaft is a belt 180, said belt passing at its intermediate portions about the guide-pulleys 179, adjustment of said latter pulleys for tensioning the belt being provided 10 by the set-screw 178.

The base-plate 157 is provided at one side with a downwardly depressed area indicated in Fig. 18 at 157', said area merging 15 into the floor of the drum by gradual inclines 157" at its ends. The drum 160 is provided with a slot 181 located at its edge and adjacent the depressed portion of the base-plate 157, thereby providing a discharge 20 opening for fasteners contained within the drum. Adjustably secured to the wall of the drum as by set-screws 182 is an apron 183 extending downwardly into said discharge opening and being provided 25 with a portion 184 deflected at substantially right angles to the body-portion of the apron. Secured upon the edge of the plate 157 at the depressed portion thereof and adjacent the discharge opening in the drum 30 are a pair of brackets 185, said brackets serving to removably position a supporting member 186, said member being provided with a projecting fin 187 (see Fig. 19) carrying at its free end a gate-member 188. 35 While the supporting member 186, the fin and the gate-member are herein shown as integral it is clearly evident to those skilled in the art that these several devices may within the scope of the invention be formed 40 as separate parts suitably secured together and it is also evident that while the support 186 is shown as formed separately from the brackets 185 the same might be integrally united therewith.

45 The gate-member 188 presents two outstanding flanges 189, such flanges serving as the inner wall of channels 190 formed between the same and the inner wall of the support 186. Within the flanges 189 are cut 50 a series of pairs of grooves or slots 191, said grooves or slots serving to permit the passage of flanged fasteners from the hopper into the channels 190, these grooves or channels being of such shape as not to permit 55 the passage therethrough of fasteners except such fasteners be in a predetermined position with respect thereto.

Fasteners such as employed in the present machine and therein described as eyelets are 60 usually formed as a short tube having an outwardly turned flange at one end thereof. It will be noted from inspection of Fig. 18 that the supporting member 186 is so located 65 with respect to the plate 157 and the outwardly turned portion of the apron 184 as

to present narrow spaces above and below the same, such spaces being of substantially the thickness of the flange of a fastener, the grooves in the gate-member being of a width substantially equal to the diameter of the 70 tubular portion of the fastener. By reason of the inclination of the brush tufts, and the provision of the depressed area in the base-plate adjacent the discharge opening, it will be seen that the brushes, which normally 75 contact with the base-plate, are relieved of such contact in passing said area, and at the same time present their free extremities substantially centrally of the gate-member 188, this providing for a uniform 80 action of the brush at both the upper and lower series of grooves 191 and at the same time securing freedom of movement of the fasteners by reason of the additional space adjacent the discharge opening provided by 85 the depressed area in the base plate of this point. It will now be appreciated that upon presentation of a series of fasteners to the gate-member by the rotation of the agitating brush such fasteners as are presented 90 with their flanges in position to enter the space between the top and bottom of the gate-member and the adjacent walls of the hopper may pass through the grooves in the gate-member and into the channels 190. As 95 will be clearly seen from this construction the fasteners permitted to enter the channels 190 form two separate series having their tubular portions opposed to each other, the flanged ends of the fasteners being 100 directed away from each other.

In fastener setting machines as previously constructed various methods of presenting fasteners in proper position to be operated on by opposed sets of fastener-setting means 105 have been employed among which may be mentioned the use of hopper devices provided with independent receptacles for fasteners each being adapted to supply a race-way—the use of single chambered drums 110 having means for separating the fasteners into two substantially independent masses with separate actuating devices therefor and with separate discharge openings,—and the use of a single chambered drum having 115 a single discharge opening and with means for reversing a portion of the fasteners after they have left said discharge opening.

It will be noted that in all of these constructions complication of parts is necessary and that with devices of this character it is necessary to employ raceways having more or less abrupt changes of curvature, or to employ reversing means between the hopper and the raceway. As is well known 120 to those skilled in the art, all such abrupt changes in curvature of the raceways and the employment of reversing means therein are fruitful sources of trouble in the practical operation of machines of this type, re- 125 130

sulting in irregular feed of fasteners and occasioning frequent stoppage of the machine with consequent annoyance to the operator, and in the present machine the endeavor has been to avoid all such sources of delay in operation by the employment of raceways having only a very gradual change of direction and the elimination of all reversing devices between the hopper and the delivery end of the raceway. The above objections and difficulties are avoided by the use of applicant's device wherein the fasteners are discharged directly from the hopper in independent reversed series and wherein such fasteners may be fed directly to two substantially like raceways which may be of the most simple form and construction necessary to lead the fasteners from their point of egress to the setting device. In the arrangement shown, the gate-member 188 is provided with a series of grooves of a given width especially adapted to permit the passage of a predetermined type of fastener although fasteners of rather widely varying sizes may be employed therein successfully, but by reason of the fact that the gate-member is removably supported it is evident that other gate members having grooves of different sizes may be provided with the machine thereby to permit the employment therewith of fasteners of any desired size or type.

As herein shown the plate 157 has attached thereto or integral therewith, at a point adjacent the discharge opening 181, the base-member 192 of the lower of a pair of raceways said base-member being connected to said plate by means of a screw 193 or other suitable means. The base-member 192 is herein shown as in the form of a flat plate extending downwardly with a gradual curvature from its support toward the delivery point for the fasteners. Cooperating with this base-plate and suitably spaced therefrom by means such as washers 194 are a pair of guide-plates 195, these plates being spaced apart to provide a channel continuous with the lower channel 190 of the supporting member 186, thereby to provide guiding means for the tubular portions of fasteners moving in said channel, the flanges thereof sliding upon the base-plate 192 and extending into the space between said base-plate and the guiding plates 195. The guiding plates are secured to the base-plate by suitable connections such as screws 196 and by removing these screws, guiding plates of various widths may be attached to the base-plate. Washers of different thicknesses may also be employed between said plates thus enabling the raceway to be adapted for use with fasteners of greatly different sizes. Secured to the base-plate 192 is a bracket 197 said bracket being provided with a threaded opening 198 having engaging

therein the clamping screw 199. The lower or discharge end of the raceway is provided with a resilient retaining finger of usual construction and arrangement. Cooperating with said bracket 197 is a second bracket 200 said bracket having a slot therein adapted to take over the screw 199 thereby providing for adjustment of bracket 200 with respect to bracket 197. The bracket 200 serves as a supporting means for the base-plate 201 of the upper raceway, said upper raceway being of substantially the same construction as the lower raceway, it therefore being unnecessary to describe the same in detail it being noted, however, that the parts thereof are relatively reversed with respect to corresponding parts of the lower race. By the above construction the receiving end of the upper raceway may be adjusted to bring it into alignment with the upper raceway or channel of the supporting member 186 such adjustment being desirable at times due to interchange of such supporting members 186 for use with different sizes of fasteners. While means has been herein described for adjusting the races for use with fasteners of varying sizes, it is also within the scope of the present invention to provide the machine with a series of interchangeable, non-adjustable races, each adapted for a given size of fastener.

No claims are made herein to the specific fastener feeding mechanism above described, which mechanism forms the subject matter of and is claimed in application Serial No. 199,499, filed October 31, 1917 by George W. Jacques.

Reciprocating means for raceways.

As in this machine the punch descends to punching position in a single operation and has no lateral movement at that time and as it is desirable that the punch pick off a fastener from the delivery end of the raceway in its downward movement it is necessary that the raceway be moved out of the path of the punch during the punching operation of the latter, and the following means has been devised whereby the delivery ends of the raceways may be reciprocated in proper time with the operation of the punch.

Mounted in a suitable opening 202 formed in the frame member 4 is an adjustable, flanged bearing sleeve 203, reference being had to Fig. 9 of the drawings for specific disclosure of this mechanism, the flange 209 of said bearing sleeve being provided as shown in Fig. 2 with a slot 204 and with a screw 205 passing through said slot and entering the bracket member 4. Mounted for rotation within said adjustable sleeve is a shaft 206 provided at its outer end with a fixed crank-arm 207, a spring 208 having one end bearing against said arm and the

other end attached to flange 209 serving to normally turn said shaft in a clockwise direction as viewed in Fig. 2 to the extent permitted by suitable stop devices to be described. Within the outer face of the flange 209 forming a portion of the sleeve 203 is formed a slot 210 said slot being provided at each of its ends with depressions 211, 212 extending inwardly below the bottom of said slot. Passing through the arm 207 and having a suitable bearing therein is a spring-pressed pin 213 having a knurled knob or handle 214 at its outer end and being provided with a projecting portion 215 adapted to move in the slot 210. Projecting transversely through pin 213 adjacent the knob 214 is a retaining pin 216. Formed within the outer surface of the arm 207 and intersecting the bearing of pin 213 is a deep notch or slot 216', a second but shallow slot being arranged in the same manner but at right angles thereto. It will now be evident that by turning said knurled knob 214 the pin 216 may be brought within the slot 216' thereby permitting the pin 213 to enter one or the other of the depressions 211, 212, in which latter position the arm 207 is locked to the flange 209 thus rendering the shaft 206 immovable, and that upon retracting pin 213 and turning the same until pin 216 enters the shallow slot, the pin 213 may be locked in retracted position, thus permitting free swinging of arm 207 within the limits of slot 210 by means to be described. Upon the inner end of the shaft 206 is fixed a crank-arm 217. At 218, see Figs. 4 and 9, is indicated a yoke member having universal connection of any desirable character with a bracket member 219, the latter serving as a support for the delivery ends of the raceways. In the embodiment herein shown the universal connection between the above parts comprises two pivotal members 220 and 221 having a link member 222 connecting the same, the members 220 and 221 being respectively mounted in yoke 218 and the bracket 219, it being evident, however, that equivalent connections are fully within the scope of this invention. Pivoted to the inner end of the yoke member 218 at the points 223 and 224 is a guide-member 225 said guide-member having suitable guiding surfaces for a slide-block 226, the latter being provided with a bearing 227 for the crank pin 19 heretofore described as extending from the end of the drive shaft 14. Pivoted upon the outer surface of said guiding member 225 at the point 228 is a vibratory link 229, said link having pivotal connection at the point 230 with the aforesaid crank-arm 217. Fixed to the sleeve 203 as by means of a screw 231 is a stop member 232 bearing at its end upon the guiding member 225 thereby serving to hold the same in proper relation to the slide-block 226 and the eccentric-pin 19. At the point 233, see Fig. 2, is formed a flat seat which may be integral with the machine frame or attached thereto, such seat being adapted to form a slide-way for the raceway supporting member 219, 70 suitable means such as the bracket-arm 236, see Fig. 16 being provided for properly positioning said member 219 with relation to the seat but permitting limited lateral movement thereof. Said member 219 is herein shown as in the form of a yoke having a lower arm 234 integral therewith, said arm having a surface for engaging the seat 233 as above noted, and an upper arm 235 adjustably secured thereto as by means of a slot 236 and set-screw 237, see Fig. 17. Secured to the lower arm 234 either directly or by the use of an intervening bracket is the base member 192 of the lower race and secured to the lower side of the upper arm 85 235 is the base member 201 of the upper raceway it being evident from this construction that by adjustment of the arm 235 with respect to the arm 234, the position of the delivery end of the upper raceway in a direction from front to rear of the machine may be varied with respect to the lower raceway. Attached to the arm 207 at the point 238 is a suitable connection 239, herein shown as a chain whereby the operator may turn 90 the shaft 206 in a counter-clockwise direction as seen in Fig. 2, that is to say, against the tension of the spring 208. In the normal operation of the machine the pin 213 will be retracted from the depressions 211, 212, 100 the projecting part 215 of said pin travelling over the bottom of the slot 210 upon actuation of the chain 239 by the operator, the spring 208, however, normally holding the pin 213 in engagement with the end 212 of 105 the slot thereby holding the crank 217 in substantially the position shown in Fig. 4. Upon actuation of the drive shaft it will be seen that the eccentric pin 19 will move the block 226 in a circular path, such movement 110 by reason of the connections comprising the relatively fixed crank 217 and the link 229 resulting in a reciprocating movement of the guide-member 225 and therewith of the yoke 219 and its connected raceways to produce a forward and rearward movement of the latter upon each rotation of the drive shaft, the eccentric pin and the cam 79 being so relatively positioned as to produce a proper timing relation of the punching operation and the raceway movement. It will now be noted that by movement of the arm 207 through the chain 239, as by means of a treadle or other suitable device the shaft 206 will be rocked in a direction to cause the 115 link 229 to approach a position of parallelism with crank 217, such movement acting to retract the yoke member 218 and therewith the raceway, subsequent motion of the eccentric-pin 19 thus failing to pre- 120 125 130

sent the raceway in position for delivery of fasteners therefrom to the punching tool.

It will be observed that the guide-member 225 constitutes a follower for the actuating element afforded by the crank-pin 19, the slide-block 226 being interposed to insure ample bearing contact between the contiguous parts, while affording a sliding connection between the two to enable the follower to move transversely of and relatively to the crank-element; also that the pin 230 constitutes a normally stationary fulcrum for the vibratory link 229 but shiftable into different angular relations with the path of movement of the crank-element 19. By reference to Figs. 4 and 9, it will be observed that the guide-member or follower 225 performs uniform up-and-down movements equal to the diameter of the circular path of movement of the crank-pin 19, and that the pivotal connection of the link 229 thereto performs equal up-and-down movements between its dotted line position represented in said figure and a position corresponding with the axis of the alined shafts 14 and 206. It therefore results that in the upper extreme position of the crank-pin 19 the link 229 in its upper position draws the follower element 225 to the left and thereby jogs the eyelet races into register with the punch elements; while in the extreme lower position of the crank-pin 19 the link assumes a position overlying the arm 217 and with its movable end at the axis of the shaft 14.

The shifting of the arm 217, and with it the fulcrum-pin 230 upwardly concentrically with the shafts 14 and 206 to a position intermediate said shafts and the pivotal pin 221 causes the outer or free end of the yoke 40 attached to the follower-member 225 to swing in an arc which is substantially vertical, of which the lower end is still coincident with the axis of the shafts 214 and 206 and the upper end is above the same. It is thus obvious that by shifting the fulcrum-pin 230 the throw of the eyelet-raceways toward and from the centering elements may be adjusted so as to bring their respective eyelets into exact register with the punch, while their retracted positions are invariably at the same fixed point, the shift of the fulcrum thus varying the amplitude of the jogging movements to and from said fixed position. If it be desired at any time in the operation of the machine to employ the same merely as a punching device, the arm 207 after being depressed as above described, may be locked in the latter position by releasing the pin 213 and allowing the same to set itself in the depression 211 thereby permanently holding the raceway out of operative relation with the punches during the operation of the machine. As at times it may be desirable to remove the raceways from ready control by the operator the other de-

pression 212 has been provided, interlocking engagement with which by the pin 213 insures the normal cooperation in each eyeletting cycle between the raceway and the punching device.

By adjustment of the bearing member 203 by means of the screw 205, the initial position of the yoke member 219 and therewith of the lower raceway may be varied, the connections described thus permitting independent adjustment of the upper and lower raceways and also simultaneous adjustment in a direction toward and from the fastener setting tools, lateral adjustment of the races being also provided by the adjustable mounting of the hopper, as above described, such adjustments being desirable and in many cases necessary for the proper operation of the machine.

Presser-foot and work-support.

Fixedly secured in any suitable manner to the frame of the machine is a work-support 240, (Figs. 4 and 10) said support having upper and lower surfaces for engaging the work, the main portion of said work support being located in a position at one side of the anvil and being provided with a forwardly and laterally extending member 241 forming an auxiliary support at the front of the anvil. Adjustably supported upon said work-support is an edge-gauge 242 said gauge acting in the usual manner to guide the inner edge of the work while it is presented to the operating tools.

This gauge comprises a saddle 242' adapted to slide upon the rearwardly extending leg 240' of work-support 240 and a pair of spaced apart arms 242^a having forwardly and laterally extending lips 243 which are preferably integral with said arms although this is not necessary. Between said arms is an open-ended slot 245 adapted to receive and to permit sidewise movement therein of the anvil member 130. The member 242^a serves as edge-guides for the material in the usual manner while the overhanging lips 243 act to retain the material upon the work support against displacement by the punch in its retracting stroke. It will be noted that these lips extend a considerable distance forward of the position of punching in the direction of feed, additional means to be hereinafter described acting on the opposite side of the punching position to hold the work against the support at this point. The saddle 242' is mounted to slide on leg 240' and is provided with a slot 242^b. In the under side of leg 240' is a recess 240^c adapted to receive and prevent the turning therein of a hexagonal nut 240^e. Passing through slot 240^b and through a suitable opening in leg 240' is a bolt having its head in the form of a thumb-lever 240^a, said bolt engaging nut 240^e. By properly positioning nut 240^e the saddle 242' is held in position on leg 240'.

240^e in the recess, bolt 240^a may be so engaged therewith as to provide for ready locking and unlocking of the slide 242' with respect to the leg 240', the hexagonal nut resting 5 in the slot permitting of a fine adjustment of the tightening action of bolt 240^b. By the above arrangement the distance of the line of fasteners from the edge of the work may be adjusted with the greatest ease, no 10 tools being necessary to accomplish the desired result.

At the point 246, see Fig. 1, is indicated a bracket acting as a support for an auxiliary work-guide 247', such guide being desirable 15 when operating upon certain classes of work.

Cooperating with the upper and lower surfaces of the work-support is a pair of presser-feet, said presser-feet being duplicates and therefore only one of the same will be 20 described. Referring now to Fig. 4, reference character 247 indicates any suitable support mounted upon the frame, said support having projecting therefrom a guide pin 248. 249 is a presser-foot device, said device comprising a sleeve 250 and a foot portion 251, said sleeve portion being provided with a lug 250^a having an open ended slot 250^b adapted to take over said guide pin 248 whereby the presser-foot is supported 25 for sliding and rocking movements. As will be noted in the view of the lower presser-foot, Fig. 4, the forward portion presents a surface curved from front to rear and is substantially wedge-shaped in section, the 30 thicker portion thereof being to the rear, thus leaving a flaring groove or notch 251^a between the forward end of the presser-foot and the work-support providing for ready insertion of the work therebetween. Slid- 35 able within the sleeve 250 is a second sleeve 252, said sleeve being threaded at its outer end for engagement with an adjusting screw 253. Located within the inner sleeve 252 and bearing upon the inner surface of the 40 presser-foot is a spring 254 said spring bearing at its opposite end upon the adjusting screw 253 the latter serving to adjustably tension the spring. Surrounding the sleeve 252 and fixed thereto near its outer end is a 45 collar 255, said collar being provided with a lug 256 having a bearing therein loosely embracing a pin 257, said pin being suitably headed as shown at 258 and having fixed engagement with one of the arms of the lever 50 25. In the initial position of the parts with the hammer-levers 72 and 73 in their fully retracted position the springs 254 may be placed under initial tension by the adjusting screws 253, such tension serving to produce 55 pressure of desired amount between the presser-foot surface and the work-support. Upon movement of the hammer-levers for producing operation of the fastener setting devices, the collar 255 will be moved there- 60 with in a direction to compress the spring 65

254 and thereby substantially increase the pressure of the presser-foot upon the material held between the same and the work-support, and such increasing pressure will occur at the moment of operation of the 70 fastener setting tools, thus serving to hold the work in proper relation thereto and at the proper time.

While in machines of the prior art, it has been common to place the work under compression during the operation of the punching or setting tools it has been common also to entirely release such pressure during the feeding movement. This, however, is found to be undesirable as the work is left at such 75 time without any means of control other than such as may be exerted by the operator. This invention seeks to avoid the above difficulty by providing at all times a certain pressure between the presser-foot and the work for holding the work between the presser-foot and the work-support, the work however, at the time of punching or setting being held with a very substantial pressure against 80 accidental displacement.

By reason of the location of the presser-foot to the right of the operating tools as shown in Fig. 1 and the extension of the work-gauge 242 having the overhanging lips 243 in a position to the rear of the operating tools the work is held at two points from any lifting action of the punch in retracting, thus providing means not usually found in the prior art for retaining the work in proper operative relation to the punching devices. It may be noted that by reason of the pivotal movement of the presser-foot about the pin 248, which movement takes place at every stroke of the hammer-members, due to the connections above described, 90 and by reason of the wedge-shape of the presser-foot 251, the work engaged by said presser-foot is forcibly fed rearwardly toward the work-gauge, this feeding action taking place at each cycle of operation of the machine, thus serving to hold the work against the work-gauge in a positive manner. It is recognized that structures of the prior art have been devised having a tendency upon 95 lateral movement of the work over the work-support to cause a feeding movement of the same toward the edge-gauge but prior to the present invention no positive mechanically operated means has been provided in machines of this character for producing a 100 feeding movement of the work in two directions at right angles to each other, that is to say, a movement laterally of the work-support for feeding the work for the fastener setting operation and a second feeding movement of the work in the direction from front to rear for holding the same against the work-gauge.

Having thus indicated the nature of the invention, and having specifically described 105

a machine embodying a preferred form thereof, we claim as new and desire to secure by Letters Patent of the United States:

1. In a fastener-setting machine having 5 punching and setting devices, work-feeding mechanism, and a fastener-supplying race, in combination, a supporting frame, a main drive shaft, actuating means for said punching and setting devices and work-feeding 10 mechanism comprising cam-followers and cams engaging the respective followers each in opposite directions and imparting positively thereto to-and-fro movements, and means also mounted on said shaft for reciprocating the race.

2. In a fastener-setting machine of the duplex type, a plurality of sets of fastener-inserting tools, a single cam-shaft, a cam-member mounted thereon and formed with 20 cam-paths upon its opposite lateral faces, cam-followers engaging the respective cam-paths and positively controlled thereby in their movements in different directions, and independent connections between the respective cam-followers and the tools of different sets.

3. In a duplex fastener-setting machine, in combination, independent groups of co-operating setting elements, feeding mechanism, an eyelet supply raceway, a drive-shaft, a feed-cam mounted thereon and provided with a peripheral cam-groove and connections with the feeding mechanism, a second cam mounted upon said shaft and having 35 in its opposite lateral faces positive cam-grooves and connections from each to a setting-element of one of said groups, an eccentric pin at one end of the drive-shaft, and connections with said raceway for moving it 40 relatively to the setting-elements, and a drive-pulley at the opposite end of said drive-shaft.

4. In a fastener setting machine, in combination, a fastener supply, a raceway for 45 conducting fasteners from said supply, automatic means for reciprocating the delivery end of said race, and means under control of the operator for moving said delivery end of the race to a non-delivering position and 50 devices under control of the operator and out of the range of action of moving parts of the machine for maintaining it in such position.

5. In a fastener setting machine, in combination, a fastener supply, a raceway for 55 conducting fasteners from said supply, automatic means for reciprocating the delivery end of said race, positively in opposite directions, controlling means adapted for actuation by the operator for moving said delivery end of the race to a non-delivering position and a manually operated device actuatable relatively to and independently of said controlling means for locking said con-

trolling means to thereby render the same 65 inoperative.

6. In a fastener setting machine, in combination, a fastener supply receptacle, a raceway leading therefrom, an actuating element, a reciprocating connection between 70 said actuating element and said raceway, a normally stationary shiftable fulcrum, a vibratory link journaled upon said fulcrum and connected with said reciprocating connection, and means for shifting the position 75 of said fulcrum to vary the working position of said link.

7. In a fastener setting machine, in combination, a fastener supply receptacle, a raceway leading therefrom, an actuating element, a reciprocating element operatively 80 connected therewith and deriving therefrom uniform to-and-fro movements in one direction while free to perform jogging movements in a direction transversely of said to-and-fro movements, an operative connection 85 between said raceway and said reciprocating element, a normally stationary shiftable fulcrum, a vibratory link journaled upon said fulcrum and connected to said reciprocating element, and means for angularly shifting the position of said fulcrum 90 relatively to said actuating element to vary the working position of said link.

8. In a fastener setting machine, in combination, a fastener supply receptacle, a raceway leading therefrom, an actuating crank element, a follower embracing and bodily movable relatively to and transversely of 95 said crank element, an operative connection 100 between said follower and said raceway, a normally stationary shiftable fulcrum, a vibratory link journaled thereon and connected with said follower, and means for shifting the position of said fulcrum to 105 change the working position of said vibratory link and thereby vary the movements of said follower relatively to said crank element.

9. In a fastener setting machine, in combination, a fastener supply, a raceway for 110 conducting fasteners from said supply, a yoke member universally connected to said race near its delivery end, a block slideable in 115 said yoke, a shaft, an eccentric pin carried by said shaft and entering said block and means connected to said yoke whereby rotation of said shaft and eccentric pin produces reciprocation of said race.

10. In a fastener setting machine, in combination, a fastener supply, a raceway for 120 conducting fasteners from said supply, a yoke member universally connected to said race near its delivery end, a block slideable in 125 said yoke, a shaft, an eccentric pin carried by said shaft and entering said block, a second shaft in alignment with said first shaft and having a crank-arm thereon, and

a link connecting said arm with the yoke whereby rotation of the eccentric pin produces reciprocation of said race.

11. In a fastener setting machine, in combination, a fastener supply, a raceway for conducting fasteners from said supply, a yoke member universally connected to said race near its delivery end, a block slideable in said yoke, a shaft, an eccentric pin carried by 10 said shaft and entering said block, a second shaft, a bearing for supporting the same in alignment with said first shaft, said second shaft being provided with a crank-arm and being angularly adjustable by the operator, 15 and a link connecting said arm and yoke whereby rotation of the eccentric pin produces reciprocation of said race and whereby adjustment of said second shaft changes the path of such reciprocation.

20 12. In a mechanism for producing reciprocating motion in a variable path, a shaft, a bearing therefor, an eccentric element carried by said shaft, a second shaft spaced from but in alignment with said first shaft, 25 an angularly adjustable bearing sleeve for said last named shaft, an arm upon the outer end of said shaft and spring means tending to turn the same, a limit pin carried by said arm and moving in a slot in said bearing 30 sleeve, means under control of the operator for moving said arm against the tension of said spring, a crank on the inner end of the last named shaft, a link pivoted to said crank, a yoke pivoted to said link, and a 35 slideable block mounted in said yoke and engaged by said eccentric element, the part to be reciprocated being pivotally connected to said yoke.

13. In a fastener setting machine of the 40 duplex type in combination, a plurality of superposed races, means for supplying the same with fasteners, and means for effecting the adjustment of the delivery ends of said races relatively to and transversely of each 45 other.

14. In a fastener setting machine of the duplex type, in combination a plurality of superposed races, means for supplying the same with fasteners, means for simultaneously reciprocating the delivery ends of said races transversely thereof, and means for independently adjusting one of said races.

15. In a fastener setting machine of the duplex type, in combination, a plurality of 55 superposed races, means for supplying the same with fasteners, a plurality of opposed fastener-inserting devices co-operating with the respective races, a connection between said races for maintaining their delivery ends in superposed relation and including means for adjusting the relative positions of said delivery ends, and mechanism for imparting to said raceways jogging movements toward and from said inserting devices and

including means for adjusting the amplitude of said jogging movements relatively to a fixed retracted position of the raceways.

16. In a material feed mechanism for fastener setting machines, in combination, a feeding element, means for varying the 70 throw of the feeding element comprising a lever pivoted at one end and having an arcuate slot therein, a link having one of its ends slidably engaged with said slot, a pair of adjustable stop devices in said slot, means 75 tending to move the link into engagement with one of said devices, and means under control of the operator for moving it into contact with the other of said devices, the link at its other extremity having connection 80 with the feeding element.

17. In a material feed mechanism for fastener setting machines, in combination, a feeding element, means for varying the 85 throw of the feeding element, comprising a lever having an arcuate slot, stop devices adjustable in said slot, a member slideable in said slot between said stops, a bellcrank-lever mounted co-pivotal with said lever, a link connecting one arm of said lever to said 90 slideable member, a member under control of the operator acting upon the other arm of said bellcrank-lever, and a coil spring acting upon said bellcrank-lever to resiliently hold said slideable member in contact with 95 one of the stop devices.

18. In a fastener setting machine, a base member, a bracket carried thereby and having an inclined supporting surface, an arm mounted upon said supporting surface and 100 provided with spaced bearing members, a lever-arm pivotally mounted between said bearing members, and a fastener inserting device carried adjacent the free end of said lever.

105 19. In a fastener setting machine of the duplex type, opposed fastener inserting instrumentalities, a pair of hammer devices for actuating the respective instrumentalities, and independent operating means for 110 positively controlling said devices.

20. In a fastener setting machine of the duplex type, opposed fastener inserting instrumentalities, a pair of hammer devices for actuating the respective instrumentalities, a pair of independent cam-paths and reciprocatory followers therefor each positively controlled by its respective cam-path in its movements in different directions, and connections between said hammer devices 115 and the respective cam-followers.

120 21. In a fastener setting machine of the duplex type, opposed fastener inserting instrumentalities, a pair of hammer devices for actuating the respective instrumentalities, a pair of independent cam-elements, and connections between said cam-elements and the respective instrumentalities for

- operating said devices, said connections including oppositely reciprocating followers each actuated positively in different directions by its respective cam-element.
5. 22. In a fastener-setting machine of the duplex type, opposed fastener-setting instrumentalities, a pair of hammer devices for actuating the respective instrumentalities, a cam-disk having independent cam-paths and followers engaging the same, of each interengaging cam-path and follower the one embracing and positively engaging both sides of the other, and connections between each hammer device and its respective 10 cam-follower.
15. 23. In a fastener setting machine of the duplex type, opposed fastener inserting instrumentalities, a pair of actuating devices each including a rocking-element for the 20 respective instrumentalities, and a cam disc having upon its opposed lateral faces independent, positive cams for operating said rocking-element.
25. 24. In a fastener setting machine of the duplex type, opposed fastener inserting instrumentalities, a pair of actuating devices for the respective instrumentalities, comprising hammer levers having parts for engaging said instrumentalities, and other 30 parts adapted to be positively operatively controlled by separate driving elements.
35. 25. A hammer for use in a fastener setting machine employing a punch and set, said hammer comprising a lever-arm bifurcated at its extremity to provide opposed, spaced arms, an angular plate secured to said lever and closing the space between said arms at one end and side thereof, a U-shaped member vertically slidable in said space, and 40 means for vertically adjusting the same, said member serving as the operating element for the set.
45. 26. In a fastener setting machine employing a punch and set, in combination, a hammer lever, a cavity in one face of said lever, a U-shaped slide vertically adjustable in said cavity, and a plate interposed between said slide and the wall of the cavity and vertically adjustable, said slide and plate forming the striking elements of said hammer.
55. 27. In a fastener setting machine employing a punch and set, in combination, a hammer-lever, a cavity in one face of said lever, a U-shaped slide vertically adjustable in said cavity, an inclined groove in said slide, a member slidable in said groove and means engaging said member for adjusting said slide.
60. 28. In a fastener setting machine employing a punch and set, in combination, a hammer-lever, a cavity in one face of said lever, a U-shaped slide vertically adjustable in said cavity, a slidable block mounted in a slot in the upper face of the hammer-lever, an inclined groove in said U-shaped slide, a tongue projecting from said block and engaging said slot, and means for adjusting said block.
65. 29. In a fastener setting machine employing a punch and set in combination a hammer-lever, a cavity in one face of said lever, a U-shaped slide vertically adjustable in said cavity, a block slidably supported in the other face of the hammer-lever and projecting between the arms of said U-shaped slide, inclined grooves in the arms of said slide and inclined tongues carried by said block and engaging said grooves, and a screw passing through the wall of the cavity 80 and having positive engagement with said block whereby the latter may be adjusted to vertically position the U-shaped slide.
75. 30. A telescopic punch and set mechanism for fastener setting machines comprising in combination a supporting sleeve, and a punch device slidable in said sleeve, said device comprising a hollow shank having an integral flange at one end, a hollow punch having a collar near its base adapted 90 to contact with said flange and a centering teat to enter the end of the shank.
80. 31. In a fastener setting machine of the duplex type, opposed fastener inserting tools, a work-support located between said tools and providing opposite work guiding surfaces, presser-feet cooperating with the respective surfaces, means for normally tensioning said presser-feet, and means acting upon the operative movement of said tools 100 to increase such tension.
85. 32. In a fastener setting machine provided with a fastener inserting tool, a hammer for operating said tool, a work support, a presser-foot, means for tensioning 105 said foot, and means connected with said hammer whereby operative movement of the same acts to increase such tension.
90. 33. In a fastener setting machine employing a punch and set and a hammer for 110 operating the same, in combination, a work-support, a spring tensioned presser-foot co-operating therewith, and means connected with said hammer for increasing such spring tension upon operative movement of 115 the hammer.
95. 34. In a fastener setting machine in combination, a tool operating hammer, a work-support, a pivotally supported presser-foot, a spring pressing said foot toward the work-support, and means actuated by the hammer 120 in its operative movement to increase the tension of said spring.
100. 35. A presser-foot for fastener setting machines comprising a member provided with 125 a presser surface, said member having a portion thereof formed as a sleeve, a second sleeve slidable therein, a spring tending to

move said sleeves in opposite directions and means acting upon said second sleeve to vary the tension of said spring.

36. A presser-foot for fastener setting machines, comprising a member provided with a presser surface, said member having a portion thereof formed as a sleeve, a second sleeve slidable therein, a coil spring acting to move said sleeves in opposite direction, a tool operating hammer and a connection between said hammer and said second sleeve, whereby operative movements of the hammer act to increase the tension of said spring.

37. A presser-foot for fastener setting machines, comprising a member provided with a presser surface, said member having a portion thereof formed as a sleeve, a second sleeve slidable therein, a coil spring acting to move said sleeves in opposite directions, said presser member being pivotally and slidably supported, a lever-arm movable at intervals in the operation of the machine, and a pivotal connection between said lever and said second sleeve, whereby operative movement of said lever serves to compress said spring.

38. In a fastener setting machine, an edge-gage for guiding the material operated upon, means for feeding material past said gauge, and positively actuated instrumentalities for forcibly feeding the material toward said gage.

39. In a punching machine, in combination, a work-support and independent positively actuated means for forcibly feeding the material operated upon in two directions substantially at right angles to each other.

40. In a fastener setting machine in combination, a work-support, a presser-foot, means to feed material over said work support in one direction and means for moving said presser-foot to thereby feed the material over said work support in another direction.

41. In a fastener setting machine in combination, a work-support, an edge-gage, a pivotally mounted presser-foot, and means for rocking said foot to thereby feed the material over said work-support toward said gauge.

42. In a punching machine, a work-support, an edge-gage, a presser device comprising a lever member having its fulcrum spaced from said work-support, and provided with a curved-faced presser-foot, tension means for said device and means for rocking said foot to thereby feed the material toward the edge-gage.

43. In a punching machine, a work-support, an edge-gage, a presser device comprising a lever member having its fulcrum spaced from said work-support, and a presser-foot carried thereby, said presser-

feet being of substantially wedge-shape in section with the thick portion thereof toward the edge-gage, means for normally tensioning said foot, and means for simultaneously rocking said foot and increasing its tension.

70

44. An edge-gage for fastener setting machines comprising a support, a saddle slidably mounted thereon and provided with a slot, a nut, a bolt passing through said slot and the support and engaging said nut, and means for turning said bolt with respect to the nut.

75

45. In a fastener setting machine, in combination, a fastener setting tool provided with an enlarged head, said tool being mounted for reciprocation toward and from setting position and for movement in a plane at right angles thereto, a hammer for striking said head to give said tool its active movement, and a resilient forked member carried by said hammer and adapted to take under said head for restoring said tool to inoperative position.

80

46. In a fastener setting machine, in combination, a fastener setting tool mounted for reciprocation toward and from setting position and in a plane at right angles to the direction of said reciprocation, a hammer movable in the direction of said reciprocation for operating said tool, and a member pivotally supported upon said hammer and adapted to engage said tool, said member upon the retracting movement of said hammer acting to withdraw the tool.

85

47. In a punching machine, in combination, a work support, and independent, intermittently acting means for feeding the work relatively to the work support alternately in two directions.

90

48. In a machine for operating on work, in combination, a punch, a lever for imparting thereto endwise punching movements, means to move the punch to feed the work, and other means connected with and actuated by said lever to feed the work.

100

49. In a machine for operating on work, in combination, a punch, actuating means for imparting thereto its punching movements, means to move the punch to feed the work, a presser foot, and means operatively connected with said actuating means to move the presser foot to feed the work.

110

50. In a machine for operating on work, in combination, a punch, means to move the punch to feed the work in one direction, a presser foot, and means to move the presser foot to feed the work in another direction.

115

51. In a machine for operating on work, in combination, a punch, actuating means for imparting thereto its punching movements, means to intermittently move the punch to feed the work, a presser foot, and means operatively connected with said actuating

120

125

means to intermittently move the presser foot to feed the work while the punch feed is inactive.

52. In a punching machine, in combination, a punch, means to intermittently move the punch to feed the work in one direction, a presser foot, and means to move the presser foot to feed the work substantially at right angles to the direction of said punch feed and while said punch feed is inactive.

53. In a machine of the class described, in combination, a work-support, work clamping means, means to actuate said clamping means to feed the work in one direction and means to feed the work in another direction, both feeds being performed relatively to said work-support.

54. In a machine of the class described, in combination a work-support, a work gauge mounted thereon, work clamping means, means to actuate said clamping means to feed the work toward said gauge, and means for feeding the work past said gauge.

55. In a fastener setting machine, a pair of punches, a pair of sets, an anvil having a pair of punch and set elements in coopera-

tive relation to said punches and sets, and a single cam disc for imparting punching and setting movement to all of said punches and sets. 30

56. In a fastener setting machine, a pair of punches, a pair of sets, an anvil having a pair of punch and set elements in cooperative relation to said punches and sets, a member, means actuated by said member for positively controlling one punch and set, and means actuatable by said member for positively controlling the other punch and the other set to punch and set fasteners simultaneously in two pieces of material. 40

57. In a fastener setting machine, a pair of punches, a pair of sets, an anvil having a pair of punch and set elements in cooperative relation to said punches and sets, a shaft, a member carried by said shaft, and connections from said member to all the punches and sets for positively controlling the same to punch and set fasteners simultaneously in two pieces of material. 45 50

In testimony whereof, we have signed our names to this specification.

GEORGE M. EAMES.

GEORGE W. JACQUES.
